FISH LURE

Albert Scalzitti, 1003 S. Halsted St., Chicago, Ill.

Filed May 10, 1963, Ser. No. 74,834

Term of patent 7 years

(Cl. D31—4)

Fig. 1

Fig. 3

FIG. 1 is a perspective view of fish lure showing my new design;

FIG. 2 is a side elevation thereof, with portions omitted for ease of illustration; and

FIG. 3 is a front elevational view.

I claim:

The ornamental design for a fish lure, as shown.
